UNITED STATES PATENT OFFICE.

HARRY N. CAIN, OF CLEVELAND, OHIO, ASSIGNOR TO THE DONLEY BROTHERS COMPANY, OF CLEVELAND, OHIO, A CORPORATION.

INSERT FOR CONCRETE.

1,314,854.

Specification of Letters Patent. Patented Sept. 2, 1919.

Application filed March 29, 1918. Serial No. 225,542.

To all whom it may concern:

Be it known that I, HARRY N. CAIN, of Cleveland, in the county of Cuyahoga and State of Ohio, have invented new and useful 5 Improvements in Inserts for Concrete, of which the following is a specification.

This invention relates to metallic means for firmly anchoring a removable bolt to structures of self-hardening plastic material, 10 such as concrete.

In the present state of the art to which this invention pertains, we are convinced after making many tests, that the market does not offer an insert of this character capable of 15 holding fast without damage to itself, or to the concrete structure, when subjected to the maximum load its bolt can sustain. Either the insert displaces so much concrete as to materially weaken the structure, or, as is 20 usually the case, its anchoring means, or its shell, bend or give way, or crumble or break out portions of the concrete, under lighter loads than the anchor-bolt is capable of bearing.

25 Therefore, the prime object of the present invention is to produce an insert capable of holding fast the greatest load its anchor-bolt can sustain, with a minimum weakening displacement of concrete. To this end, the anchorage of the insert is formed to meet directly the strains to which it is subjected, whereby less metal is required than to sustain indirect strains; and the anchoring roots are spread apart to receive a large and 30 strong mass of concrete between them. A further object is to provide practically for receiving and holding in an insert bolts of 35 different sizes.

Minor objects will become apparent from 40 the following description of a preferred embodiment of the invention, reference being had to the accompanying drawing, in which:—

Figure 1 is a side elevation of the insert.

45 Fig. 2 is a longitudinal section of the insert shell taken on the center line.

Fig. 3 is a view of the bottom, or face, of the device.

Fig. 4 is an elevation sectioned on line 50 4—4 of Fig. 1.

Fig. 5 is a section like Fig. 4 showing the insert embedded in concrete, and a small sized bolt therein.

The reference letter *a* indicates the hollow 55 body portion, or shell of the insert, and *b*

and *b'* are its prong-like anchoring roots; its form being suitable for a casting of iron, steel or other metal. In service the insert is embedded in the concrete, or other plastic hardening material, of a wall, ceiling or 60 floor structure, as shown at *c*, Fig. 5, the plane face *d* of the device being flush with the outer surface of the concrete.

The usual, or any suitable laterally projecting flanges *e* are provided, each being 65 recessed to receive a nail *f* to secure the insert in place on the false wood work, or mold boards, before the concrete is poured in and tamped about it. After the concrete has hardened and the form boards removed 70 therefrom, the nails *f* may be cut off flush with the surface, as shown in Fig. 5.

Extending lengthwise along the greater portion of both sides of the face *d* of the shell *a* are strong inwardly projecting 75 flanges *g*, forming a bolt-slot *h* therebetween, which slot leads into a wider rectangular opening *i* at one end, and is terminated by the shell wall at its other end; thus forming a keyhole-shaped aperture in the face of 80 the insert for the reception of a bolt and its adjustment longitudinally of the device.

The inner surfaces of the side and end walls of the shell *a* extend at right angles to the face *d* to about the height of the head 85 of a bolt which they and the slot *h* are fitted to receive, such a bolt being indicated by dotted lines at *j*, Figs. 2 and 4. The side walls should be tapered on their outer sides, as shown in section in Figs. 4 and 5, so as 90 to be heavier adjacent to the flanges *g*. The inner wall or cover of the shell *a* is curved, as shown, opposite the opening *i*, so that the head, or nut, of a bolt *j* may be inserted through the said opening by tilting it; but 95 the main portion of the cover is inclined inwardly from the end walls as at *k*, and from the side walls as at *l*, the sides *l* meeting at a sharp median angle, like an inverted V as shown in section in Figs. 4 and 5. 100

The anchoring means comprise two straight root-arms *b* and *b'* branching from the cover of the shell *a*, their center lines lying in the central longitudinal plane of the insert, but making equal angles with a 105 transverse plane perpendicular to the face *d*. The horns *b* and *b'* are strongly filleted to the inclined walls *k* and *l*, and, as seen in Fig. 1, taper smaller toward their terminations; but, as seen in Fig. 4, they are much 110

broader, and taper larger toward their outer ends to provide anchorage. The said members *b* and *b'* terminate respectively in knobs *m* and *m'*, being flange-like protuberances 5 extending laterally on all sides; and these knobs are intended to resist the major part of the pull of the bolt.

As shown in Fig. 2, the branching center lines of *b* and *b'* meet the center line of 10 the normal position of the bolt *j* at the plane of the under side of the bolt-head. Thus, the resultant of the reactions of *b* and *b'* coincides with the middle or normal position of the center line of the bolt, and 15 the force lines of *b* and *b'* meet at the normal central point of application of the pull of the bolt against the insert. Therefore, it should be readily understood that the straight anchor-arms *b* and *b'*, and the inclined sides *k* and *l* serve to transmit the 20 pull of the bolt *j* to the anchorage very directly; and the mass of concrete between the said anchor-arms, which must crumble before the insert can loosen, is large and 25 strong, and properly shaped to resist the strain.

A smaller sized bolt than *j* may be used in the insert, as shown at *j'*, Fig. 5, by providing it with a square washer *n*. The bolt-head and washer can be inserted through 30 the opening *i*, and, when resting against the flanges *g*, the bolt-head is raised high.

enough to be kept from turning by the inclined walls *l*.

I further point out and distinctly claim 35 as my invention:

1. In an insert for concrete, a hollow body adapted to receive and seat a removable bolt projecting therefrom, a pair of anchoring arms branching straight throughout their 40 lengths from the inner side of said body so as to receive between them a V-shaped longitudinal section of concrete, said arms being flattened transversely and tapered, and flange-like protuberances on the extremities 45 of said arms.

2. In an insert for concrete, a hollow body adapted to receive and seat a removable bolt projecting therefrom, a cover formed by inclined inner portions of the end and side 50 walls of said body, the side walls of said cover forming a sharp salient angle at the center line of the device adapted to receive and engage bolt-heads of various widths, and arms branching from the said cover and 55 provided with anchoring means.

In testimony whereof I affix my signature in the presence of two subscribing witnesses, at Cleveland, Ohio, this 20th day of March, 1918.

HARRY N. CAIN.
